UNITED STATES PATENT OFFICE.

ANTHONY GEORGE MALDON MICHELL, OF MELBOURNE, VICTORIA,
AUSTRALIA.

IMPULSE-TURBINE.

SPECIFICATION forming part of Letters Patent No. 760,898, dated May 24, 1904.

Application filed July 14, 1903. Serial No. 165,457. (No model.)

To all whom it may concern:

Be it known that I, ANTHONY GEORGE MALDON MICHELL, civil engineer, a subject of the King of Great Britain, residing at Commercial Union Chambers, No. 409 Collins street, Melbourne, in the State of Victoria and Commonwealth of Australia, have invented an Impulse-Turbine, of which the following is a specification.

- 10 My invention relates to a turbine devised for a new mode of operation or rule of action; and the essential novelty consists in the arrangement of an impulse-turbine wheel with a circumferential ring of curved vanes approximately tangential at their outer ends and approximately radial at their inner ends, said vanes extending inwardly for about one-third of the radius and surrounding a relatively large central space which allows of the flow 15 of the water transversely in a manner and for a purpose hereinafter disclosed. The wheel in operation is acted on by a nearly tangential jet or jets of water which both enters and is discharged by the outer ends of the vanes. 20 The course of the water within the wheel is, however, entirely different at different speeds of rotation, and to produce these different effects is the object of the special construction which I employ. 25 After describing the construction of the turbine in connection with the drawings I will more fully explain the mode of action and its advantages.

It is to be understood that the wheel may be employed with its shaft either vertical or horizontal, its action being the same in both cases.

In the accompanying drawings, Figure 1 is an elevation, partly in section, of the turbine-wheel and nozzle. Figs. 2 and 3 are vertical sections taken at right angles to Fig. 1 of two forms of the wheel. Fig. 4 is a sectional view corresponding to part of Fig. 1, showing a divided inlet-nozzle. Figs. 5 and 6 are diagrammatic elevations illustrating the action of the wheel. Figs. 7 and 8 are views similar to Figs. 2 and 3, showing modes of construction suited to special circumstances.

The turbine-wheel consists of two circular

disks or shrouds (marked A A in all the figures) and of vanes B B, which are arranged in an annular series around the circumference of the wheel and between the shrouds. In Fig. 2 both shrouds A A are shown provided with bosses C C for mounting upon the shaft D, which is continuous through the wheel. Fig. 3 shows an overhung wheel mounted upon the shaft D by means of a single boss C upon one shroud.

The vanes B B, as shown in Figs. 1 and 4, are curved, so as to be nearly tangential at their outer ends and diverging toward their inner ends, said inner ends extending substantially radially to the disks, as shown. The vanes occupy only the outer portion of the space between the shrouds, preferably extending inward for approximately one-third of the radius, the relatively large inner space being open and in free communication with the spaces between the vanes. The angle between the circumference of the wheel and the vanes at their outer ends, though small—that is to say, not more than about thirty degrees at most—must be greater than the angle at which the jet of water meets the circumference. The inner ends of the vanes are preferably exactly radial if the shaft, as in Fig. 3, does not enter the space between the shrouds; but when, as shown in Figs. 1 and 2, the shaft passes through the wheel the vanes are to be only approximately radial and directed to the front side of the shaft, reckoning in the direction of the motion of the vane, as indicated in Fig. 1.

The water may be applied to the wheel either in a single jet from a nozzle of circular or other section, as E, Fig. 1, or from a nozzle with guide-vanes, as shown at e e, Fig. 4. The latter arrangement, which is well known in the art, is particularly suitable for the operation of my turbine with large quantities of water, as it enables a large jet to be directed nearly tangentially in all its parts. The width of the nozzle in all cases is to be somewhat less than the width of the wheel between its shrouds.

The construction of the wheel being as described, its action is as follows: The water de-

livered in a nearly-tangential jet will at starting and at low speeds of the wheel pass inwardly through the ring of vanes and nearly diametrically across the central air-space and will be discharged by the vanes opposite to those through which it entered. This action is shown in Fig. 1, in which the streams of water are indicated by dotted lines. At working speeds, on the contrary, the inwardly-moving water is retarded on account of the rapid rotation of the wheel, comes nearly or quite to rest upon the vanes, and then reverses its motion and is redischarged from their outer ends without crossing the central space. This action is shown in Fig. 6, in which the dotted circle indicates the inner edges of the vanes. At intermediate speeds of the wheel the water follows an intermediate course, as shown in Fig. 5, traversing the inner circular open space upon a chord, which lies the farther from the center the higher the speed. The working peripheral speed of the wheel is rather greater than one-half of the velocity of the jet. With the vanes extending through one-third of the radius the water will be retained in the vanes, as shown in Fig. 6, when the peripheral speed exceeds three-fifths of the velocity of the jet. I find that at the working and all lower speeds the water is chiefly discharged at a point in space approximately opposite the point of entrance and that at all such speeds the pressures acting on the vanes at these points combine to turn the wheel, but largely counterbalance one another's tendencies to cause lateral pressure on the bearings. This would not be the case at low speeds if the water were not discharged across the central space. Also, the water being retained at high speeds between the vanes into which it is delivered, irregular scattering and fluid-friction are then minimized, while by the transverse delivery at low speeds the discharged water is prevented from fouling the incoming jet. To fully attain this last advantage, it is preferable when the axis of the wheel is horizontal to deliver the jet at or near the highest point of the circumference and discharge it near the lowest point. I find that if the vanes extend through much more than one-third of the radius the spaces between their inner ends will at working speeds be too narrow to carry the water, and the proper action will be interfered with. If, on the other hand, the vanes are much shorter, the working speed of the wheel must be so high as to lead to loss of efficiency.

In order to enlarge the spaces between the inner ends of the vanes I may make the shrouds, as shown in Fig. 7, somewhat concave on their inner sides, thus making the vanes wider at their inner than at their outer ends.

As a convenient means of utilizing large quantities of water I may combine two or more of my wheels, as shown in Fig. 8. In this construction the shrouds A A, with their bosses C C, are formed exactly as in Fig. 2; but intermediate disks F F are employed, which together with the shrouds support several rings of vanes B B. Each set of vanes may have its own nozzle, or a single nozzle may be employed of sufficient width in the direction of the axis to supply all the sets of vanes.

Having now particularly described and ascertained the nature of my said invention and in what manner the same is to be performed, I declare that what I claim is—

1. An impulse-turbine water-wheel, comprising a shaft, a pair of circular disks fixed on said shaft, a series of curved vanes arranged between the circumferential portions of said disks, said vanes being curved in the same direction and extending through approximately one-third of the radius of the disks, the outer ends of said vanes extending approximately tangentially to the disks, said vanes diverging toward their inner ends, and said inner ends extending substantially radially to the disks, all so arranged that an inner central air-space is formed which communicates only with the spaces between the vanes, thus subjecting the latter to the transverse flow of the water, substantially as shown and described.

2. An impulse-turbine water-wheel comprising a pair of circular disks concave on their adjacent inner sides, and an annular series of curved vanes arranged between the circumferential portion of said disks and extending through approximately one-third of the radius of the wheel, said vanes being arranged nearly tangential at their outer ends and nearly radial at their inner ends, substantially as described.

In testimony whereof I have hereunto set my hand in presence of two subscribing witnesses.

ANTHONY GEORGE MALDON MICHELL.
